MOISTURE DETERMINATION BALANCE

Robert E. Ohaus, Westfield, N.J., assignor to Ohaus
Scale Corporation, Union, N.J., a corporation of New
Jersey

Filed Oct. 21, 1959, Ser. No. 58,012

Term of patent 14 years

(Cl. D52—1)

Fig. 1 is a perspective view of a moisture determination balance showing my new design;

Fig. 2 is a rear elevational view of the same;

Fig. 3 is a front elevational view of the same; and

Fig. 4 is a side elevational view of the same.

The undisclosed side of the instrument is substantially the same in appearance as the side shown.

I claim:

The ornamental design for a moisture determination balance, as shown and described.
